(57) **CLAIM**

The ornamental design for a multipurpose hook as shown and described.

DESCRIPTION

FIG. 1 is a front, right, top perspective view of a multipurpose hook showing my new design;

FIG. 2 is a back, left, bottom perspective view thereof;

FIG. 3 is a front view thereof;

FIG. 4 is a back view thereof;

FIG. 5 is a top view thereof;

FIG. 6 is a bottom view thereof;

FIG. 7 is an enlarged left view thereof;

FIG. 8 is an enlarged front, right, top perspective view of component 1 of the multipurpose hook shown separately for clarity of disclosure;

FIG. 9 is an enlarged back, left, bottom perspective view thereof;

FIG. 10 is an enlarged front view thereof;

FIG. 11 is an enlarged back view thereof;

FIG. 12 is an enlarged top view thereof;

FIG. 13 is an enlarged bottom view thereof;

FIG. 14 is an enlarged left view thereof;

FIG. 15 is a front, right, top perspective view of component 2 of the multipurpose hook shown separately for clarity of disclosure;

FIG. 16 is a back, left, bottom perspective view thereof;

FIG. 17 is a front view thereof;

FIG. 18 is a back view thereof;

FIG. 19 is a top view thereof;

FIG. 20 is an enlarged left view thereof; and,

FIG. 21 is a use state diagram of the multipurpose hook. The right view of the components is a mirror image of the left view of the components, so the right view of the components is omitted;

the right view of the 1st component is a mirror image of the left view of the 1st component, so the right view of the 1st component is omitted;

the right view of the 2nd component is a mirror image of the left view of the 2nd component, so the right view of the 2nd component is omitted;

the bottom view of the 2nd component is the same as the top view of the 2nd component, so the bottom view of the 2nd component is omitted.

(Continued)

The broken lines shown on the drawings depict portions of the multipurpose hook that form no part of the claimed design.
